UNITED STATES PATENT OFFICE

EDWIN E. SLICK, OF PITTSBURGH, PENNSYLVANIA

GLASS WORKING APPARATUS

Application filed March 24, 1927. Serial No. 177,919.

The present invention relates broadly to the art of glass working and more particularly to an apparatus adapted to operate upon successive gathers or charges of glass to effect a shaping thereof. Certain features of the invention are useful in connection with the handling of materials other than glass, and it will therefore be understood that if desired, the apparatus may be utilized with such materials.

It is customary in the art to which the present invention relates, to provide glass working apparatus comprising a relatively movable mold carrier and shaping elements adapted to effect a shaping operation either by pressing, blowing, or both. It is one of the objects of the present invention to provide an improved apparatus embodying such relatively movable mechanisms and effective for producing in rapid succession, articles of the desired characteristics.

Another object of the present invention is to provide super-imposed carriers of different dimensions and movable about different axes, one of the carriers supporting the molds and the other of the carriers supporting the shaping elements, the carriers being so arranged that at predetermined time intervals the molds and elements may travel in the same path irrespective of the eccentric relationship of the carriers.

Still another object of the present invention is to provide a plurality of shaping elements adapted to be brought into use successively with successive molds, the shaping elements being fewer in number than the number of molds.

Still another object of the present invention is to provide effective means for bringing the shaping elements into the desired operative relation with a mold and thereafter destroying such operative relation, and effecting such movement of the shaping elements while in inoperative position as to insure substantially uniform wear thereof.

The term shaping elements is herein used generically as a word of definition including within its scope pressing or blowing means,

such as plungers, blow heads or the like, and is not used as a term of limitation.

In the accompanying drawings, there are shown for purposes of illustration only, certain preferred embodiments of the present invention, it being understood that the drawings do not define the limits of my invention as changes in the construction and operation disclosed therein may be made without departing either from the spirit of the invention or the scope of my broader claims.

In the drawings:

Fig. 1 is a top plan view of one form of apparatus constructed in accordance with the present invention;

Fig. 2 is a side elevation of the apparatus shown in Fig. 1;

Fig. 3 is a detail elevational view illustrating the operation of one form of delivery mechanism for the glass;

Fig. 4 is a vertical sectional view on the line IV—IV of Fig. 1 looking in the direction of the arrows;

Fig. 5 is a top plan view on an enlarged scale illustrating the shear mechanism, its operating means, and the relationship of the superimposed carriers;

Fig. 6 is a partial top plan view of the carrier for the shaping elements;

Fig. 7 is a view partly in plan and partly in section, illustrating the cooperation of the shaping elements and molds;

Fig. 8 is a top plan view of the inner control cam for the shaping elements;

Fig. 9 is a side elevation of the cam shown in Fig. 8;

Fig. 10 is a side elevation of the outer control cam looking toward the inner face thereof;

Fig. 11 is a top plan view of the shears showing the same closed for shearing;

Fig. 12 is a view similar to Fig. 11 showing the shears in normal open position;

Fig. 13 is a sectional view along the line XIII—XIII of Fig. 11;

Fig. 14 is a detail sectional view illustrating a modified form of discharge for the formed articles; and,

Fig. 15 is a detail view partly in section

and partly in elevation illustrating a form of delivery mechanism adapted to replace that of Fig. 3.

In accordance with the present invention, there may be provided either a portable or a stationary apparatus, the drawings illustrating a portable unit comprising a base 2 mounted on suitable wheels 3.

Secured to the base and projecting upwardly therefrom, is a pedestal 4 through which extends a central shaft 5. Rotatably mounted with respect to the pedestal and shaft, is a carrier in the form of a table 6, which table is provided on its upper surface with a plurality of molds 7 of such construction and contour as to effect the desired shaping operation on the plastic material delivered thereto. Secured to the carrier 6 in any desired manner is a ring gear 8 herein illustrated as meshing with a pinion 9 driven from a worm wheel 10 in the gear housing 11. The worm wheel is in turn driven by a worm 12 through the frictional driving connection 13 including a gear 14 meshing with the pinion 15 on the armature shaft of a suitable motor 16. By reason of this construction, it will be apparent that as the motor is operated the table will be turned at the desired speed, it being apparent that a variable speed motor may be utilized to insure a speed range in the movement of the carrier.

Also secured to the base 2 and projecting upwardly therefrom is a bracket 17 carrying a roller 18 in such position as to underlie the periphery of the carrier 6 and maintain the same in the desired plane while the plastic material is being shaped in the molds.

Extending between the upper end of the shaft 5 and the upper end of a supporting rod 19 carried by the bracket 17, is a cross head 20. Suitably mounted within this cross head is a shaft 21 constructed to cooperate at its intermediate portion with an inner cam 22 and at its lower portion with a second carrier 23. It will be noted that the carrier 23 is of much smaller diameter than the carrier 6 and that it is rotatable about the axis of the shaft 21 eccentrically disposed relative to the shaft 5.

The secondary carrier 23 is provided with an upper flange 24 and a lower flange 25. The upper flange 24 is formed with a series of equidistantly spaced elongated openings 26 through which openings project bushings 27 having mounted therein plunger heads 28. These plunger heads are shaped at their upper ends to roll against the peripheral face 29 of the inner cam 22, and are formed with an enlargement 30 suitably beveled to effectively cooperate with the upstanding flange 31 on the inner cam. This flange as will be apparent more particularly from Figs. 8 and 9 of the drawings, has a broken away portion 32 which permits the plunger heads 28 to drop downwardly when this point is

reached in their travel. From the depression 32 the cam starts preferably in such manner as to provide a relatively steep leading edge portion 33 adapted to effect delivery of a plunger head to the main body of the cam around which it travels until it drops from the end 34 into the depression 32. Adjacent the depression 32 the inner cam 22 has a peripheral portion 35 formed about the longitudinal axis of the shaft 5 as a center. 75

Carried by the cross head 20 and projecting downwardly from the lower side thereof, in such position as to lie substantially opposite the peripheral portion 35 of the inner cam 22, is an outer cam 36. This outer cam has an inner face 37 curved about the axis of the shaft 5 as a center, and therefore lying in concentric relationship to the peripheral portion 35 on the inner cam 22. The path between the cams is symmetrically disposed with respect to the center line of the molds 7 whereby during the rotation of the carrier 6, the molds successively pass below the cam path formed by these cams and in line therewith. It is during this period that the plunger heads 28 are permitted to lower and bring the shaping elements carried thereby into cooperative relation with the plastic material in the respective molds. During the maintenance of this cooperative relationship, the parts continuously travel, such a travel being permitted by reason of the fact that temporarily the plunger heads, with their associated parts, leave the path of travel defined by the upper carrier and travel in the path determined by the cams, which path is concentric with the path of travel of the molds 7.

The operation of the apparatus is such that the main carrier rotates in the direction of the arrow A of Figs. 1 and 7 while the second carrier 23 rotates in the direction of the arrow B of these figures. During this rotation, the plunger heads 28 being in contact with the outer periphery 29 of the inner cam 22 and the enlargements 30 on the plunger heads being in travelling contact with the cam surface 31, the plunger heads are continuously rotated during this travel. When they reach the point 34, they are permitted to drop down. Thereafter, they remain in their lowered position until the enlarged portions 30 of the heads 28 engage the lifting portion 38 of the outer cam 36. Continued rotation of the respective carriers causes the enlargements 30 to climb up the lifting portion 38 of the cam until they are high enough to be transferred to the steep leading portion 33 of the inner cam and thence to the gradually inclined portion 31. In actual practice it has been found desirable to effect the initial lifting of the plungers by the outside cam due to its greater radius of curvature as well as its greater distance from the center of the carrier 6, whereby a greater arcuate travel of the plunger 125 130

heads is required to effect the lifting operation, this making the lifting more gradual than would otherwise be the case.

In order to insure proper continued registration or cooperative relation of the respective carriers such that the proper relationship is always maintained therebetween, the lower flange 25 is preferably shaped in the form of a star wheel as will be clearly apparent from Fig. 1, thereby providing a series of teeth 39 with intervening recesses 40. The teeth and recesses are so shaped that they are adapted to cooperate with the molds 7 during the travel of the carriers 6, so that these molds serve by reason of their engagement with the lower flange 25 to rotate the secondary carrier. This precludes possibility of one of the carriers getting out of the desired cooperative relationship.

Each of the plunger heads is adapted to carry desirable shaping mechanism or elements which may be in the form of blow heads, press heads, plungers or the like. In the accompanying drawings, I have indicated a press machine, and therefore these elements are in the form of press heads 41. Each press head, as illustrated in detail in Fig. 4, has an upstanding stem 42 fitting in a suitable recess in its corresponding plunger head 28, the parts being held in assembled relation by a bolt 42a. Surrounding each of the stems 42 and shaped to embrace its cooperating press head 41, is a movable mold part 43 comprising a downwardly projecting flange 44 adapted to fit over the upper end of each of the molds 7 and thereby define a confining cavity for the glass article G being formed. Each mold part 43 is preferably urged downwardly by means of a compression spring 45, these springs being operative as will be clearly apparent from the drawings for permitting a relative movement between the press heads 41 and the mold parts 43.

With the plunger heads in their lowered positions, the mold parts 43 are in the cooperative relation illustrated in section in Fig. 4 with respect to the molds 7. The travel of the carriers brings the plunger heads successively under a pressure roller 45a having trunnions 46 mounted in bearings 47 which are urged downwardly by springs 48. By reason of this construction, as the plunger heads pass beneath the pressure roller, the press heads are urged downwardly to exert the desired pressure on the plastic material within the mold cavities formed by the molds 7 and the mold parts 43.

It will be apparent to those skilled in the art, that the plastic material may be delivered to the molds in any desired manner, either by hand or by means of a suitable feeder. In the embodiment of the invention illustrated in the accompanying drawings, there is disclosed a portion of a glass furnace F having a suitable outlet opening through

which the glass g as indicated in Figs. 3, 13 and 15, is adapted to issue in the form of either a continuous or intermittent stream.

Suitably located adjacent the discharge orifices of the furnace is suitable severing means for the glass adapted to form charges C therefrom as indicated in the figures of the drawings referred to. These severing means may comprise shear blades 49 having V-shaped cutting portions 50 so arranged as to effect the conclusion of the shearing operation at substantially the center line of the stream of plastic material. The shear blades may be pivotally connected by a pin 51 which also forms a pivotal mounting for the blades. This pivotal mounting is so located that the shearing ends of the blades are relatively long while the opposite ends 52 are relatively short. The ends 52 may be provided with pins

53 projecting therefrom in such manner as to engage cam slots 54 in a cross head 55. The cross head is mounted for reciprocation in a suitable guide-way 56, and is adapted to be operated by the piston rod 57 connected to a suitable piston 58 in a fluid pressure cylinder 59.

This fluid pressure cylinder may be provided with suitable connections 60 and 61 in the opposite ends thereof adapted to alternately serve as inlets and exhaust ports. These connections lead to opposite sides of a four-way valve 62 as illustrated in section in Fig. 5.

The valve is provided with an inlet 63 and with an exhaust 64. With the parts in the position of Fig. 5, fluid under pressure will be admitted to the connection 61 to effect movement of the piston to the right as viewed in the drawings, the parts being shown in Fig. 5 as having just completed this travel.

The next quarter movement of the valve will be effective for passing fluid under pressure from the inlet 63 to the connection 60 while permitting the connection 61 to exhaust. The valve is adapted to be operated to effect 90° movements thereof by

means of a stem 65, Fig. 6 carrying a star-wheel 66 at its lower end adapted to be engaged by projections 67 on the secondary carrier 23. These projections 67 are preferably formed on a ring 68 which is adjustably held in position by a set screw 69, whereby the ring

68 may be moved circumferentially of the secondary carrier to slightly change the relationship between the projections 67 thereon and the shaping elements. Such an adjustment is desirable inasmuch as it permits the time of shearing to be varied with respect to the position of the carriers, and thereby accurately control the time of delivery of the sheared charges.

These charges may be delivered to the molds 7 in any desired manner, different embodiments of delivery chutes being illustrated respectively in Figs. 3 and 15. In Fig.

3 there is shown a chute 70 having a pivotal mounting 71 adjacent its upper end whereby

125

130

it is adapted to swing from the dotted line position of Fig. 3 to the full line position of this figure. This movement may be effected by providing the lower end of the chute with a projection 72 adapted to be engaged by lugs 73 projecting upwardly from the carrier 6. The lugs are so located that during the travel of the carrier they successively engage the projection 72 and cause the chute 70 to temporarily move at an instantaneous speed equal to the speed of travel of the carrier and with the discharge of the chute in line with a mold cavity. With such a construction, proper delivery of the glass to the molds, is insured.

With the form of the invention of Fig. 15, the chute 70' has a pivotal mounting 71' at its upper end and an adjustable connection 74 at its lower end whereby it is held in predetermined inclined position. This inclination is so figured with respect to the speed of movement of the carrier 6 that proper delivery of the charges to the molds is obtained.

The finished ware may be removed from the molds in any desired manner, different forms of mechanism being shown for this purpose in Figs. 4 and 14 respectively. Referring to Fig. 4, it will be noted that each of the molds 7 has a movable portion 75 projecting downwardly below the carrier 6 in such manner as to engage a cam 76 fixedly mounted on a bracket 77 projecting upwardly from the base 2. This cam tends to raise the plungers and thereby lift the formed articles G out of the cavities in the molds 7. In this position they may be mechanically engaged by a suitable transfer device 78 which may be actuated by the lugs 73 before referred to to effect movement from the full line position of Fig. 4 to the dotted line position.

With certain types of ware, however, I have found it desirable to utilize an off-take device of the character shown in Fig. 14 and comprising an air blast nozzle 78 adapted to subject the formed ware to a blast of air effective for lifting the same as indicated diagrammatically in Fig. 14 and effect discharge through a suitable trough 79.

It will be understood that suitable means, not shown, but such as customarily provided in the art for delivering air for cooling purposes to the molds and to the plastic material therein, may be provided at suitable points.

While the particular construction of the severing means constitutes no important part of the present invention, the mechanism herein shown possesses desirable characteristics, and is specifically claimed in my copending application Serial No. 266,601 filed April 2, 1928. By reason of the construction shown, a complete shearing cycle comprising a closing, shearing, and opening movement is effected by a single stroke of the piston 58. The return stroke in each case effects a simi-

lar complete cycle. This insures a much more rapid shearing operation than has heretofore been obtained with apparatus in which a movement of the piston in one direction was relied upon for accomplishing the closing movement of the shears and the shearing operation, while a stroke in the opposite direction was relied upon to open the shears.

The present invention lends itself to the rapid formation of articles from plastic material while insuring accuracy of registration of the parts at all time. A high speed of production is obtained by reason of the use of continuously movable carriers whereby the time ordinarily lost where an intermittent rotation is necessitated, is saved and devoted to suitable shaping operations.

Other advantages of the present invention arise from the provision of a plurality of carriers mounted in superimposed relationship and of different diameters where the axes of the respective carriers are eccentric one with respect to the other and compensating means is provided to permit the parts of the respective carriers to travel in a common path during a part of their travel.

Further advantages arise from the provision of cooperating shaping elements carried by superimposed carriers of different diameters eccentrically mounted and constructed to permit cooperative relation of the shaping elements of the respective carriers during movement thereof.

Still further advantages arise from the provision of shaping elements adapted to move vertically during rotational movement thereof in combination with lifting means on one cam for effecting the lifting of the shaping elements and means, on another cam for maintaining the elements in lifted position.

Still further advantages of the invention arise from the provision of a carrier in which shaping elements are mounted for radial movement toward and from the center thereof, whereby they are permitted to travel in paths having different radii of curvature during different portions of the cycle in combination with means for effecting rotation of the shaping elements to insure uniformity of wear thereof.

I claim:

1. In a plastic shaping apparatus, a plurality of rotatable carriers, one of said carriers being of smaller diameter than the other and vertically off-set relatively thereto, said carriers being rotatable about stationary eccentric axes, shaping elements on the respective carriers, and means for causing the shaping elements on the carrier of smaller diameter to periodically travel concentrically to the path of travel of the elements on the carrier of larger diameter.

2. In a plastic shaping apparatus, a plurality of rotatable carriers, one of said carriers being of smaller diameter than the other

and vertically off-set relatively thereto, said carriers being rotatable about stationary eccentric axes, shaping elements on the respective carriers, and means for causing the shaping elements on the carrier of smaller diameter to periodically travel concentrically to the path of travel of the elements on the carrier of larger diameter, one of said carriers being driven by the other.

3. In a plastic shaping apparatus, a plurality of carriers movable about separate axes and axially superimposed, a plurality of shaping elements on each of the respective carriers, and means for moving one of the carriers by the other only through the medium of the shaping elements on one of said carriers.

4. In a plastic shaping apparatus, a carrier of major diameter having a plurality of shaping elements thereon, a carrier of minor diameter vertically spaced with respect to said first mentioned carrier and having shaping elements thereon, each carrier having a single axis only about which it is movable and means periodically operable for causing the shaping elements of the respective carriers to travel in a common path.

5. In a plastic shaping apparatus, a carrier of major diameter having a plurality of shaping elements thereon, a carrier of minor diameter vertically spaced with respect to said first mentioned carrier and having shaping elements thereon, each carrier having a single axis only about which it is movable and means periodically operable for causing the shaping elements of the respective carriers to travel in a common path, said means comprising stationarily mounted means adapted to temporarily change the path of travel of the elements on at least one of said carriers.

6. In a plastic shaping apparatus, a carrier of major diameter having a plurality of shaping elements thereon, a carrier of minor diameter vertically spaced with respect to said first mentioned carrier and having shaping elements thereon, and means periodically operable for causing the shaping elements of the respective carriers to travel in a common path, said means comprising a cam path cooperating with the elements on the carrier or minor diameter for changing the path of travel of such elements.

7. In a plastic shaping apparatus, a main carrier, a secondary carrier above the same, eccentrically disposed stationary axes about which the carriers rotate, shaping elements mounted on each of said carriers, the shaping elements of one of the carriers being movable radially thereto and means for periodically causing said shaping elements to move in a common path.

8. In a plastic shaping apparatus, a main carrier, a secondary carrier above the same, eccentrically disposed stationary axes about

which the carriers rotate, shaping elements mounted on each of said carriers, the shaping elements of one of the carriers being movable radially thereto and means periodically effective for changing the path of travel of the shaping elements of the secondary carrier to cause it to conform to the path of travel of the elements on the main carrier.

9. In a glass working machine, a main axially mounted carrier having molds thereon, a second carrier mounted on a fixed axis superimposed in an axial and offset direction to the first carrier and having shaping elements thereon adapted to cooperate with said molds and normally moving in a different path, the number of molds exceeding the number of shaping elements, and means operative at predetermined points in the travel of the respective elements for causing them to move in a common path.

10. In a plastic shaping apparatus, a carrier movable only about a single axis, a plurality of shaping means carried thereby, a second carrier eccentrically mounted relative to the first carrier and movable only about a single axis, shaping means movable mounted on the second carrier for cooperation with the first-named shaping means, and means for moving the shaping means when in material shaping relation through identical arcuate paths of substantial length.

11. In a plastic shaping apparatus, a carrier movable only about a single axis, a plurality of shaping means carried thereby, a second carrier eccentrically mounted relative to the first carrier and movable only about a single axis, shaping means carried by the second carrier for cooperation with the first-named shaping means, and means for confining the shaping means when in material shaping relation in identical arcuate paths of substantial length.

12. In a plastic shaping apparatus, a carrier movable only about a single axis, a plurality of shaping means carried thereby, a second carrier eccentrically mounted relative to the first carrier and movable only about a single axis, shaping means carried by the second carrier for cooperation with the first-named shaping means, and concentric guiding surfaces associated with said carriers for controlling the movement of the shaping means when in material shaping relation.

13. In a plastic shaping apparatus, a carrier movable only about a single axis, a plurality of shaping means carried thereby, a second carrier eccentrically mounted relative to the first carrier and movable only about a single axis, shaping means carried by the second carrier for cooperation with the first-named shaping means, and concentric guiding surfaces associated with said carriers for controlling the movement of the shaping means when in material shaping relation, one

of said guiding surfaces constituting a camming surface.

14. In a plastic shaping apparatus, a rotatable carrier mounted on a fixed pivot, a plurality of shaping means carried thereby, a second carrier eccentrically mounted relative to the first-named carrier on a stationary pivot, shaping means carried thereby for cooperation with the first-named shaping means and movable at substantially the same peripheral speed, and means for causing the shaping means to traverse identical arcuate paths of substantial length while in material shaping relation.

15. In a plastic shaping apparatus, a plurality of rotatable carriers, means for imparting continuous rotation to one of the carriers about a fixed pivot, one of said carriers being of smaller diameter than the other and vertically offset relative thereto, a stationary pivot for said smaller carrier, shaping elements on the respective carriers, and means for causing the shaping elements on the carrier of smaller diameter to periodically travel along the arcuate path of travel of the elements on the carrier of larger diameter for a substantial distance.

16. In a plastic shaping machine, a continuously driven carrier having a working surface extending in substantially a horizontal plane, upwardly opening shaping elements carried thereby, a second separately supported carrier movable in a different path from that of the first-named carrier and in timed relation thereto, vertically movable shaping elements carried by the second carrier for cooperation with the first-named shaping elements, means for supplying glass gathers to successive shaping elements on one of the carriers, means for bringing successive shaping elements on one carrier into engagement with the shaping elements on the other carrier for shaping the gathers, means for maintaining said elements in vertical alignment during their travel through a substantial distance, and means for automatically removing the shaped articles.

17. In a plastic shaping machine, a continuously driven horizontally extending carrier, shaping elements carried thereby, a second carrier movable in a different and independent path than the first-named carrier and in timed relation thereto, shaping elements carried by the second carrier for cooperation with the first-named shaping elements, means for supplying glass gathers to successive shaping elements on one of the carriers, means for bringing successive shaping elements on one carrier into engagement with the shaping elements on the other carrier and moving in the same arcuate path therewith for a substantial distance while shaping a gather, and means for automatically removing the shaped articles.

18. In a plastic shaping machine, a carrier

movable in substantially a horizontal plane, shaping elements carried thereby, a second carrier movable in a different path from that of the first-named carrier and in timed relation thereto, means for separately supporting said carriers, shaping elements carried by the second carrier for cooperation with the first-named shaping elements, means for supplying glass gathers to successive shaping elements on one of the carriers, means for bringing successive shaping elements on one carrier into engagement with the shaping elements on the other carrier for shaping the gathers, means for maintaining said elements in vertical alignment during their travel through a substantial distance, and means for automatically removing the shaped articles.

In testimony whereof I have hereunto set my hand.

EDWIN E. SLICK.
